UNITED STATES PATENT OFFICE.

RICHARD F. JOHNSON, OF ROCKFORD, ILLINOIS.

CHILD'S FOLDING CHAIR.

No. 834,383.

Specification of Letters Patent.

Patented Oct. 30, 1906.

Application filed August 25, 1905. Serial No. 275,740.

To all whom it may concern:

Be it known that I, RICHARD F. JOHNSON, a citizen of the United States, residing at Rockford, Illinois, have invented a certain new, useful, and Improved Child's Folding Chair, of which the following is a full, clear, and exact description, such as will enable others skilled in the art to which it appertains to make and use the same.

10 My invention relates to improvements in children's chairs, and has special reference to improvements in folding or portable chairs for infants.

15 The object of my invention is to provide a child's or infant's chair that shall be portable, that shall be of small size, of little weight, and foldable so that it may be collapsed into a neat package.

20 A further object of this invention is to provide a chair of the foregoing description adapted for attachment to the back of an ordinary chair.

25 Still further objects of my invention will appear hereinafter.

30 My invention consists generally in a child's folding chair comprising individually-foldable and relatively collapsible side frames having hooks for attachment to the backs of an ordinary chair in combination with a collapsible chair-back suspended between said side frames; and, further, my invention consists in various details of construction and combinations of parts, all as hereinafter described, and particularly pointed out in the 35 claims.

35 My invention will be more readily understood by reference to the accompanying drawings, forming a part of this specification, and in which—

40 Figure I is a perspective view of my novel chair in place upon an ordinary chair, the ordinary chair being shown in dotted lines.

45 Fig. II is a perspective view of the chair as it appears when partially folded. Fig. III shows the chair completely folded and wrapped in its seat fabric, and Fig. IV is a sectional detail of the locking device for the table.

50 As shown in the drawings, my invention is a two-legged chair having rear legs only. These are adapted to rest on the seat of an ordinary chair, and the upper ends of these rear legs contain hooks by which the device is secured to the top of the larger chair.

55 The essential portions of the device are two foldable side frames which comprise the

standards or rear legs 1 1, the arms 2 2, and the braces 4 4. The arms or bars 2 2 are pivoted in respective clips 3 3 and are adapted to be folded against the upper end of the 60 standards or legs. The braces have their upper ends pivoted to respective arms by rivets 5 at points near the forward ends thereof, and their lower ends are pivoted upon clips or sleeves 6 6 that are slidable upon the lower 65 parts of respective standards 1 1. The sleeves 6 6 are stopped by fixed clips or collars 11 11 on the lower ends of the standards, and it is obvious that when the arms are in the position shown in the drawings the structure will support considerable weight. The lower ends of the standards contain or are provided with rubber feet 29, which prevent the marring of the bottom of the larger chair.

70 The standards or rear legs 1 1 are preferably tubes, and in these I arrange the shanks of the rubber-covered hooks 30. The shanks are adjustable in the standards and when the hooks have been pressed down over the back of a chair may be secured by the thumbscrews shown at the upper end of the standards. The hooks do not sustain the weight of the folding chair, but prevent the latter from tipping forward or sidewise on the larger chair. The lower ends of the 85 standards are held apart by a collapsible bar 7 7, comprising parts 8 8, joined by a pivot 9 and having their ends attached to the collars 11 by pivots 10. The arrangement is such that when distended the pivot 9 drops below 90 the pivots 10 to prevent the accidental collapse of the bar.

95 The upper ends of the standards need not be held apart and are merely joined by a cord or fabric having loops or eyes 19 fastened on the shanks of the hooks 30. The chair is provided with a detachable table 12, resting on the arms 2 2.

100 To at once secure the table in place and afford the requisite rigidity to the chair, I provide the table 12 with two metallic parts 13 13. These form sockets for the ends of the arms 2 2. The table is secured or locked in place by two spring-latches 14 14, preferably extending through the socket-pieces 13 and 105 adapted to drop into notches 15 in the arms. The ends of the arms are rounded or beveled to lift the latches as the table is pushed onto them. The latches 14 must be sprung up before the table can be lifted from the arms.

110 Two essential members or elements of the side frame consist in hangers 22 22, having

holes 21 21 at their lower ends. These hangers are pivoted on the rivets 5 5 and may be thrown into line with the arms, as shown in Fig. 2. Their backward movement is limited by lugs or stops 23 on the braces 4. The chair back and bottom are suspended between the cord 18 and the lower ends of the hangers 22 22. As a means of attaching the forward end of the seat to said hangers I preferably employ a cross-rod 21. One end of the rod has a groove and shoulder 25, detachably holding it in the hanger 22. The other end of the rod has a knob 24 and is bent, as at 25^a, so that the rod may be thrown with the side frame members to facilitate folding the chair. It is obvious, however, that the rod may be withdrawn from both hangers at such times, if desired.

As a back and bottom for the folding chair and also to serve as a wrapper for the frame thereof I employ a sheet of cloth 17, having open plaits, which accommodate the cord 18 and the rod 21. It is obvious that the cloth may be removed from the latter and when thus removed may be used for wrapping the collapsed members of the chair, the ends 26 27 of the cloth making neat ends for the package and being secured by the cords 28 28, as shown in Fig. 3.

As various modifications of the structure herein shown will readily suggest themselves to one skilled in the art, I do not confine my invention to the specific construction herein shown and described.

Having thus described my invention, I claim as new and desire to secure by Letters Patent—

1. In a device of the class described, two legs having adjustable hooks at their upper ends, and provided with feet or cushions at their lower ends, in combination with arms having their ends pivoted upon said legs midway thereof, braces having their upper ends pivoted near the free ends of said arms and their lower ends slideable on said legs, stops on the legs for said braces, a table detachably held upon and bracing said arms, and a seat suspended from the forward ends of said arms and the upper ends of said legs, substantially as described.

2. In a device of the class described, two foldable sides, each comprising one leg, one arm and one brace and each provided with a hanger, a table detachably secured on said arms, and a seat adjustably suspended from the tops of said legs and the lower ends of said hangers, substantially as described.

3. In a device of the class described, two legs adapted to rest on a chair-bottom and

foldable arms projecting therefrom, means extending between respective legs and arms for supporting the latter, hangers, 22, depending from said arms, a table slidably attached to the free ends of said arms, and a seat suspended from said legs and having its forward edge detachably connected with said hangers, substantially as described.

4. In a device of the class described, two collapsibly-connected and individually-foldable side frames, including arms having notched forward ends, a detachable seat suspended between said side frames, and a table having latches and sockets fitting the notched ends of said arms, substantially as described.

5. A device of the class described, comprising, in combination, legs, 1 1, having adjustable hooks at their upper ends, arms, 2 2, pivoted on said legs, pivotal braces, 4 4, having their lower ends slideable on said legs, hangers, 22 22, pivoted on said arms, and having holes in their free ends, a collapsible brace extending between the lower ends of said legs, and a seat flexibly attached to the upper ends of said legs, and at its lower end having fastenings detachably held in the holes in said hangers, substantially as described.

6. In a device of the class described, two legs, 1 1, having adjustable hooks upon their ends, in combination with arms, 2 2, pivoted to respective legs, hangers, 22 22, depending from said arms, suitable collapsible supports joining the free ends of said arms to said legs, a seat detachably secured to the said hangers and to said legs, and a table, 12, having parallel sockets to receive the free ends of said arm, substantially as described.

7. In a device of the class described, two legs, 1 1, having cushions at their lower ends, in combination with hooks, 30, having shanks slideable in said legs, arms, 2 2, pivoted upon respective legs, collapsible braces, 4 4 extending between respective arms and legs, a table detachably secured on the free ends of said arms, and a cloth seat suspended from the forward ends of said arms and from the tops of said legs, and adapted to enfold the parts named when collapsed, substantially as described.

In testimony whereof I have hereunto set my hand, this 22d day of July, 1905, in the presence of two subscribing witnesses.

RICHARD F. JOHNSON.
